UNITED STATES PATENT OFFICE.

HERMAN L. HOHLFELD, OF PHILADELPHIA, PENNSYLVANIA.

DESIGN FOR A TURKISH TOWEL OR MAT.

47,561.

Specification for Design.

Patented July 13, 1915.

Application filed May 18, 1915. Serial No. 28,972. Term of patent $3\frac{1}{2}$ years.

To all whom it may concern:

Be it known that I, HERMAN L. HOHLFELD, a citizen of the United States, residing at Philadelphia, State of Pennsylvania, have invented a certain new, original, and ornamental Design for a Turkish Towel or Mat, of which the following is a specification, reference being had to the accompanying drawing, forming a part thereof.

The figure is a plan view of a section of a

Turkish towel cut transversely and showing my new design.

I claim:

The ornamental design for a Turkish towel or mat, as shown.

HERMAN L. HOHLFELD.
